UNITED STATES PATENT OFFICE.

FRANK L. ROWNTREE, OF SOUTH MERIDEN, CONNECTICUT, ASSIGNOR TO THE R. & H. MANUFACTURING COMPANY, OF HARTFORD, CONNECTICUT, A CORPORATION OF CONNECTICUT.

PACKAGE-VENDING MACHINE.

1,152,051.

Specification of Letters Patent.

Patented Aug. 31, 1915.

Application filed October 19, 1914. Serial No. 867,327.

To all whom it may concern:

Be it known that I, FRANK L. ROWNTREE, a citizen of the United States, residing at South Meriden, county of New Haven, State 5 of Connecticut, have invented an Improvement in Package-Vending Machines, of which the following is a specification.

This invention relates to coin controlled vending machines by which packets or packages, as of postage stamps, chewing-gum, or chocolate are dispensed, and has for its object to provide simple and inexpensive means for protecting the owner of the machine against dishonest operators and for protecting operators against the loss of coins, my present improvement rendering it practically impossible for the operator to lose a coin without securing a package in return, or to secure more than one package for a 20 coin.

With these and other objects in view I have devised the novel improvement in coin-operated package vending machines which will be hereinafter described and then specifically pointed out in the claims hereunto appended.

In the accompanying drawings forming a portion of this specification, Figure 1 is a front elevation of the machine with the eas- 30 ing removed; Fig. 2 a plan view partly broken away; Fig. 3 a side elevation partly broken away, of the operative parts, as seen from the left in Figs. 1 and 2, and Fig. 4 is a perspective view of the coin holder de- 35 tached.

10 denotes the base which in use is rigidly secured to a table or counter, 11 standards extending upward therefrom, 12 a bed secured to the standards and provided with a 40 depending ledge 13, and 14 package compartments having openings 15 in front through which the packages 16 may be seen and through which the weight 17 may be seen when a compartment becomes nearly ex- 45 hausted.

In the drawings I have illustrated a machine having two package compartments. The principle of operation is the same however whether one or a plurality of package 50 compartments is provided.

18 denotes a sliding carrier as a whole. For convenience I will use the singular form and describe a single carrier. Each carrier comprises an upper horizontal portion 19, a 55 lower horizontal portion 21, a vertical por-

tion connecting said horizontal portions, an abutment 22 depending from the lower horizontal portion, lugs 23 extending laterally from the horizontal portion and engaging ways 24 on the under side of the ledge, and 60 coin ways 25, depending from the front of the horizontal portion, which receive the edges of an operating coin in use. The coin, indicated by dotted lines only, is dropped into a slot 26 at the back of ledge 13, and 65 passes into the coin ways, the edge of the coin below the ways engaging the edge of a coin holder 27, secured to the under side of the ledge, which will presently be fully described. 70

28 denotes the ejector which is adapted to reciprocate over the face of the bed and is secured to the carrier by a rivet 29 which passes through a slot 30 in the bed.

31 denotes a push rod which is adjustably 75 secured to a slide 32 adapted to reciprocate on a fixed rod 33. In the present instance there are two slides and two rods for them to slide on, the slides being connected together and made rigid by a cross rod 34. Each 80 push rod is preferably blunt pointed at its forward end to avoid friction upon a coin when it is released, as will be more fully explained. The rear end of each push rod has threaded engagement with the correspond- 85 ing slide and is locked in position after adjustment by a nut 35. Each abutment 22 is provided with a clearance slot 36 for the push rod and each push rod is provided with a cross pin 37 adapted to engage the front 90 of the abutment to return the carrier after each forward movement. The slide and push rod are actuated by means of a plunger 38 which passes through the ledge and is provided with a head 39 for convenience in 95 operation.

40 denotes a bell crank lever pivoted as at 41 to a bracket 42 which depends from the bed. The lower end of the plunger is loosely pivoted to one arm of the bell crank 100 lever, the other arm of said lever having pivoted thereto a link 43 and the other end of said link being connected to the corre- 105 sponding slide. Preferably the link is branched (the branches not being shown in the drawings), the ends of the branches being pivoted on cross rod 34. The parts are returned to their normal position after each forward movement by a spring 44, one end of which is connected to the bell crank lever 110

and the other end to a fixed portion of the structure, as to the under side of the bed, or to bracket 42. The rear of each package compartment is provided at its lower end 5 with a slot 45.

46 denotes a support in front of the package compartment on which a portion of the casing (not shown) rests, this portion of the casing being ordinarily of glass or provided 10 with windows through which openings 15 may be seen. Under support 46 are slots 47 through which the packages are ejected. Each time the carrier and ejector are moved forward, the ejector will pass into slot 45 15 and push out the lowest package in the compartment, passing under the package just above it. The lowest package is forced out through slot 47, under the support, into position to be conveniently removed by the 20 operator. When there is no coin in the machine, operation of the plunger will force the slide and push rod forward, but will have no effect on the carrier, consequently no package 25 will be ejected.

25 To obtain a package the operator must drop a coin of the proper denomination into coin slot 26. The coin will pass down coin ways 25 and its lower edge will rest against the edge 48 of coin holder 27. The operative 30 edge of the coin holder is preferably inclined backward and inward. At the front end of the incline is a shoulder 49, the front end of the coin holder being preferably cut away as at 50 to provide clearance for the 35 coin when it is released. The operator having placed a coin of the proper denomination in the coin ways next presses down upon the plunger which actuates the slide and push rod. As the push rod moves forward, 40 it engages the coin and moves the carrier forward causing the ejector to push out a package while the coin is moving forward along the inclined edge of the coin holder. Up to the time the coin has reached shoul- 45 der 49 the ejector will not have moved a package forward far enough to permit the operator to remove it, but after the coin has passed the shoulder the package will have been moved by the ejector into position to be 50 removed. Should the operator, however, after having moved the ejector forward just far enough to enable him to remove the package, attempt, by relieving the pressure on the plunger, to save his coin, this will be 55 prevented by the action of the shoulder of the coin holder, which will be engaged by the coin and will stop backward movement of the carrier. It will be readily understood from Fig. 2 that the shoulder is so far forward of the coin slot as to render it impossible to remove the coin after a package has been delivered, as the instant the pressure upon the push rod is relieved the push rod 60 will move backward away from the coin 65 which will drop down into the receptacle pro-

vided for it. In other words, a package cannot be removed from the machine until the coin has been carried so far forward that the shoulder of the coin holder will lock the carrier against backward movement when the 70 pressure on the push rod is relieved. It should be noted that the instant, in the forward movement of the carrier, that the coin ways have passed beyond the coin slots, the forward end of the lower horizontal portion 20 75 of the carrier will block the coin slot corresponding with the compartment from which a package has been removed, and the other coin slot will be blocked by the corresponding push rod which will be lying under it. 80 This insures that should an operator remove a package in proper manner from the machine, but without quite completing the downward movement of the plunger, leaving the coin held by the push rod, the coin 85 ways and the shoulder of the coin holder, and the slide, carrier and ejector locked against return movement, a second operator can run no risk of losing a coin, as both coin slots will be blocked and will remain so 90 until pressure upon the plunger has completed the forward movement of the parts and the release of the coin, after which the spring will return the parts to their normal 95 position so that a package can be removed in proper manner. It will be understood of course that where there are two or more package compartments, the push rods corresponding with each compartment will be moved forward each time the plunger is 100 pressed downward, but no carrier and ejector will be operated unless a coin has been placed in the corresponding coin ways, and furthermore, that a package may be removed from either compartment or from all simultaneously if coins are placed in the corresponding coin ways. 105

Having thus described my invention I claim:

1. In a machine of the character described, a sliding carrier provided with a coin receiving portion and an abutment; a push rod arranged adjacent the abutment to engage a coin in the coin receiving portion and having a lateral extension arranged in advance of the abutment for engagement therewith upon the return movement of the push rod; a slide connected with the push rod; guide means for the slide; means to move the slide in one direction; automatic means to return the slide to the starting position; and a coin holder arranged near and beneath the coin receiving portion with one of its edges disposed to engage the edge of the coin, said coin holder having a shoulder disposed forwardly of said edge, said shoulder being adapted to be engaged by the coin and thereby lock the carrier against backward movement should the forward movement thereof not be completed. 130

2. In a machine of the character described, a sliding carrier provided with a coin receiving portion and an abutment; a push rod arranged adjacent the abutment to engage a coin in the coin receiving portion and having a lateral extension arranged in advance of the abutment for engagement therewith upon the return movement of the push rod; a slide connected with the push rod; guide means for the slide; a pivoted bell crank lever; a link connecting the bell crank lever with the slide; a plunger connected with the bell crank lever to move it; a spring connected with the bell crank lever 10 to return the same to the normal position;

and a coin holder arranged near and beneath the coin receiving portion with one of its edges disposed to engage the edge of the coin, said coin holder having a shoulder disposed forwardly of said edge, said shoulder being adapted to be engaged by the coin and thereby lock the carrier against backward movement should the forward movement thereof not be completed.

In testimony whereof I affix my signature 25 in presence of two witnesses.

FRANK L. ROWNTREE.
